UNITED STATES PATENT OFFICE

MICHEL Y. REYNDERS, OF PINEY FORK, OHIO

FENCE POST

Application filed March 27, 1930. Serial No. 439,392.

This invention relates to new and useful improvements in fence posts, and has more particular reference to metallic fence posts.

The primary object of this invention is to provide a metallic fence post, of simple, durable and inexpensive construction in which the fastening device is made a part of the post, and further to provide a metallic fence post which may be readily employed as a substitute for the ordinary wooden fence post and which may be readily and easily driven into the ground for anchoring therein.

Other objects and advantages of the invention will become apparent during a study of the following description, taken in connection with the accompanying drawings, wherein:

Figure 1 is a front elevation of my improved fence post.

Figure 2 is a side elevational view thereof. Figure 3 is a longitudinal detail sectional view taken substantially on the line 3-3 of Figure 1.

Figure 4 is a transverse horizontal view taken substantially on the line 4-4 of Figure 3.

Figure 5 is a side elevational view of the upper portion of the post looking at the post from the opposite side of that shown in Figure 2.

With reference more in detail to the drawings, it will be seen that the body portion of the post is composed of a single piece of sheet metal so bent as to be substantially U-shaped in cross section and including a back portion 5 and spaced parallel coextensive sides 6 and 7 extending at right angles to the back portion and terminating at their lower ends inwardly from the corresponding ends of said back portion 5. The sides 7 and 6 at said lower ends are beveled as at 8, while the extended lower end of the back portion 10 is tapered to provide a penetrating point 9 to facilitate the driving of said lower end of the post into the ground.

Welded or otherwise secured to the fence

post and extending transversely thereof across the vertical lower edges of the sides 7 and 6 is a substantially arcuate shape anchoring plate 10, the anchoring plate being relatively thin throughout its length so as to no wise impede the progress of the post when the same is being driven into the ground.

However, it will be noted that the anchoring plate 10 is of such configuration and projects a suitable distance laterally of the sides 7 and 6 as to retard withdrawal of the post and also brace the post laterally.

The side 6 of the fence post is provided with a plurality of vertically spaced slots 11, which slots 11 are somewhat arcuate leading downwardly and inwardly from the forward edge of the side 6 as clearly suggested in Figure 5. Arranged on the other side 7 is a plurality of vertically spaced slots or notches 12, which notches 12 are also somewhat arcuate and lead inwardly and upwardly from the forward edge of said side 7. The notches 11 are arranged in staggered relation with respect to the notches 12.

The notches 11 and 12 are arranged in pairs. One notch 11 and one notch 12 constitutes a pair. As clearly suggested in Figures 1 and 2, the inner end of the notches of the respective pairs terminate in substantially transverse alignment.

In placing the fence wire 14 in the slots of the respective pairs, it will be seen that the wire is placed, first in one of the slots of the pair and then placed in the other slot of the pair for positioning within the slot at the end of the slot in a manner clearly shown to advantage in Figure 1.

To retain the wires 14 taut within the slots of the respective pairs, the back portion 5 has formed integrally therewith a plurality of vertically spaced lugs 15 which lugs 15 are arranged in vertical alignment and extend at right angles from said back portion 5 in spaced relation to the sides 6 and 7.

As shown to advantage in Figures 1 and 90

3, there is one of such lugs 15 for each pair of notches. The lugs 15 taper toward their free vertical edges and at said edges are notched or otherwise formed to provide concaved end portions 16 for engaging that portion of the wire extending between the sides 6 and 7.

As shown to advantage in Figure 4, the lugs 15 terminate slightly inwardly from the vertical forward edges of the sides 6 and 7 but at their free ends the lugs 15 project beyond the inner end of the slots of the respective pairs for pressing that portion of the wire 14 against which it engages outwardly as at 14' to tauten the wire 14 for securely locking the wire within the notches of the respective pairs.

From the foregoing then it will be seen that I have provided a thoroughly practical and reliable metallic fence post wherein the means for securing fence wires to the post are integral with the post and that such means insures a secure engagement of the wires with the fence post.

25 Even though I have herein shown and de-
scribed the preferred embodiment of my in-
vention, it is to be understood that the same
is susceptible to changes fully comprehended
by the spirit of the invention as herein de-
30 scribed, and the scope of the appended claims.

Having thus described my invention, what I claim as new is:

1. A fence post comprising a body of **U**-shape in horizontal cross section, and having pairs of oppositely disposed notches in its sides for receiving the horizontal wires of a fence, said fence post being further provided with a plurality of vertically spaced lugs formed thereon between said sides, there being one lug for each of said pairs of notches, each of said lugs terminating beyond the inner end of the notches of the respective pairs for engaging that portion of the fence wire extending between the sides of the post.

2. A fence post comprising a metallic body of U-shaped formation in horizontal section and including a back portion and a pair of spaced parallel side portions, each of said side portions having a plurality of vertically spaced notches formed therein, said notches being arranged in pairs, the notches on one side opening inwardly from the forward edge of said one side below the opening of the notches in the other side, the notches of the respective pairs having their inner ends terminating in transverse alinement, the notches of the respective pairs adapted to receive therein a fence wire, said back portion having a plurality of longitudinally spaced lugs formed thereon projecting in parallel spaced relation to said sides, there being one lug for each of said pairs of notches, said lugs at their free ends having arcuate faces for engaging 65 that portion of the wire in the notches of the

respective pairs extending between said sides for exerting a tension upon the wires for retaining the latter in the respective pairs of notches.

3. A fence post comprising a body provided with a pair of transversely spaced notches for receiving the wire of a fence, and a lug projecting from one side of the body between the notches and engaging with the portion of the fence wire extending between the notches. 70 75

In testimony whereof I affix my signature.
MICHEL Y. REYNDERS.
